V. OREGGIA

SMOKE PUMP

Filed April 17, 1925

Inventor:
Vittorio Oreggia
by Dunkleberg
attorney.

UNITED STATES PATENT OFFICE.

VITTORIO OREGGIA, OF SAN REMO, ITALY.

SMOKE PUMP.

Application filed April 17, 1925. Serial No. 23,864.

To all whom it may concern:

Be it known that I, VITTORIO OREGGIA, a subject of the King of Italy, resident of San Remo, Italy, have invented certain new and useful Improvements in Smoke Pumps, of which the following is a specification.

The present invention relates to smoke pumps as are generally used in connection with honey bees, when the bees are approached for service.

The invention provides for an apparatus simple in construction and efficient in working and capable of being operated by swinging up and down the hand holding it, as if it were a pistol.

A further object of the invention is to provide for efficient removable means for a continuous production of smoke.

The nature of my invention will be made clear by the specification and annexed drawing in which:

Fig. 1 is a sectional view of the improved pump.

Fig. 2 is a plan view of the same.

Fig. 3 is a cross section on the line A—B of Fig. 1.

The apparatus comprises a cylindrical metallic body —1— provided at the back end with bellows —2— of the usual cylindrical construction, working between the wood partitions —3—4—.

A further partition —5— is provided at the back portion of the body —1—, forming with partition —4— an air chamber —6—; while holes —7—, in said partition —5—, are arranged in front of nozzles —8—, on the partition —4— which provide a communication between the interior of the bellows and the chamber —6—.

The cylindrical wall of the chamber —6— is provided with holes —9— to feed the bellows with air, from the atmosphere.

A receptacle or basket —10—, made of wire netting, provides a well ventilated furnace, where any smoke-producing-substance is combusted.

Said basket is lodged within the body —1— and fitted between the cylindrical wall thereof, leaving a convenient space —11— for the draft. The forward end of the basket —10— is connected through a chain —12— to a projection —13— depending from a funnel-like cover —14— pivoted at

—15— and provided with a lock spring —16—, adapted to engage the flange —17— on the body —1— when the apparatus is in operation.

By opening the cover —14—, the basket will be drawn out and permit a rapid inspection of the burning substances or the easy removal or change of the same.

For handling the apparatus, a grip —18— with two arms —19—20— is provided. The ends of said arms are respectively linked or articulated to projections —21—22—, depending from the cylindrical body (1) and the back partition —3— of the bellows, the latter being movable for the action of the bellows.

The operation is as follows:

The operator holds the apparatus with one hand applied either to the grip —18— or to the arm —19— and while the smoke is produced within the body —1— and the cover —14— is shut up, the hand is swung up and down. The swinging movement of the hand, will cause, by inertia and gravity, the operation of the bellows and air jets merge from the nozzles —8— pass through the holes —7— and drive the smoke out, through the tube —23—.

For convenience of operation the said tube piece —23— is made adjustable about the axis of the apparatus.

Having now particularly described the nature of my invention and the manner in which the same should be performed I claim:

A smoke pump comprising a cylindrical body with cylindrical bellows connected to its rear end, partitions in said body forming an air chamber, nozzles projecting from one of said partitions and leading air from said bellows, holes in the cylindrical wall of said air chamber, holes in the second partition in alignment with said nozzles, a basket made of wire netting and fitted within said body, a funnel like cover pivoted to the body a chain linking said basket to the cover, a double arm grip, with two arms each of which is articulated to depending projections from said body and said bellows.

In testimony whereof I have affixed my signature.

VITTORIO OREGGIA.
